UNITED STATES PATENT OFFICE.

LINUS L. KARNS, OF ROCK ISLAND, ILLINOIS, ASSIGNOR TO THE BABCOCK & WILCOX COMPANY, OF BAYONNE, NEW JERSEY, A CORPORATION OF NEW JERSEY.

MEANS FOR FORMING BOILER-HEADERS.

1,322,116.

Specification of Letters Patent. Patented Nov. 18, 1919.

Application filed May 5, 1917. Serial No. 166,643.

To all whom it may concern:

Be it known that I, LINUS L. KARNS, a citizen of the United States, residing at Rock Island, in the county of Rock Island 5 and State of Illinois, have invented certain new and useful Improvements in Means for Forming Boiler-Headers, of which the following is a specification.

This invention relates to means for forming serpentine headers, for use in water tube boilers, and more particularly to the manner of forming the sectional core or mandrel therefor, the object of the invention being to provide a core possessing the desired amount of flexibility and one which will conform closely to the shape of the inner walls of the header, and which can be readily removed for reuse.

The invention will be understood by reference to the accompanying drawings in which Figure 1 is a vertical section through the two dies showing a tube in position, and a sectional core in the tube; Fig. 2 a similar view on the plane of the line 2—2 of Fig. 25 4 showing the header as formed from the tube of Fig. 1, and the position of the parts of the core after the dies have acted; Fig. 3 a sectional plan view on the plane of the line 3—3 of Fig. 2; Fig. 4 a transverse section on the plane of the line 4—4 of Fig. 2, the core being removed; Fig. 5 a transverse section of the header showing one of the core blocks therein; Figs. 6 and 7, are, respectively, side and top views of the core 30 block illustrated in Fig. 5; Fig. 8 a vertical section of a portion of the header showing several of the core blocks therein; Figs. 9, 10 and 11 are detail views of one form of core block; Figs. 12, 13 and 14 detail views 35 of another core block, and Figs. 15, 16, 17 and 18 detail views of still another form of core block, all as used in building up the core to produce the header of Fig. 2; Fig. 19 is a vertical section and part side view 40 of another form of header showing the location of the core blocks after the dies have acted; Fig. 20 is a plan view of the assembled core of Fig. 19 within a tube, the latter being shown in section; Fig. 21 is a central horizontal section through Fig. 20 showing the core expanded within the tube; Fig. 22 is a plan view of the header of Fig. 19 after it has been formed with stepped tube seats; Figs. 23 to 26 both inclusive show details 45 of one form of core block; Figs. 27 to 31

details of another form of core block; Figs. 32 to 35 details of another form of core block; Figs. 36 to 40 details of still another form of core block; and Figs. 41 and 42 details of a fifth form of core block, all as 60 used in the building up of the core for the formation of the header of Fig. 19. Similar reference numerals indicate similar parts in the several views.

Referring to Figs. 1 to 18, the numeral 1 designates the stationary jaw or member of a die, and 2 the movable jaw or member between which the tube 3, to be formed into a header, is placed. The tube is confined laterally between a side plate 4 integral 70 with the stationary member 1, and a movable plate 5. The members 1, 2, 4 and 5 are to be assembled in any suitable press, and the members 2 and 5 are so mounted as to be moved by hydraulic or other suitable 75 well-known means. In practice, the tube to be made into a header is first brought to a rectangular form before inserting the core or dies.

To insure the accurate formation of the 80 header a core is provided composed of a series of separate blocks 6 and 7, preferably of cast iron, having their working faces rounded to conform to the die faces. These blocks are arranged in groups of four there 85 being two sets of similar blocks in each group. Each of the blocks 6 and 7 is composed of four parts, as shown in Figs. 9 to 14 inclusive and when the parts are assembled a central opening 13 is provided to 90 accommodate a rod 8. The latter is threaded at each end to receive nuts 8' which bear against pressure blocks 9 between which and the blocks 6 and 7 when assembled upon the rod 8, are special end blocks 10. The core 95 blocks 6 and 7 and the blocks 9 and 10 are assembled in a trough upon the rod 8 and clamped by the nuts 8'. The core is then inserted into the tube 3, as shown in Fig. 1. The tube with its core when placed in 100 the press between the dies 1 and 2, are held firmly in position by the wedge 11 inserted between one end of the core and the end wall 12. The blocks 6 and 7 are so held as to permit their lateral movement during the 105 pressing operation.

As shown in Figs. 9 to 11 the blocks 6 consist of four similar pieces having beveled meeting surfaces *a* and *b*. The blocks 7, shown in Figs. 12 to 14, also consist of four 110

similar pieces having beveled meeting surfaces *c* and *d*. The blocks 10, shown in Figs. 15 to 18, also consist of four similar pieces having beveled meeting surfaces *e* and *f*. The slots 13 in the assembled blocks 6 and 7 through which the rod 8 is passed, is long enough to permit the lateral movement of the blocks to their ultimate positions, the rod itself being held stationary 10 in the openings in the end blocks 10.

The header of Fig. 2 is set in the boiler inclined to the vertical with the boiler tubes entering at right angles thereto. In Figs. 19 to 21 I have shown an assembled core 15 adapted for use in forming headers 14 which are set vertically in the boiler and in their final form have stepped tube seats 15 so that the tubes 16 enter the headers at an angle of approximately 75 degrees to the body thereof, but at right angles to the seats, as shown in Fig. 22. The core blocks for 20 this form of header are shown in detail in Figs. 24 to 42 inclusive. They are arranged in groups of four blocks each, two of the blocks being indicated by the numeral 17 and two by the numerals 18 and 18'. All 25 of the blocks have their working faces made to conform to the cross sections of the surfaces of the dies with which they coöperate. They are trapezoidal in cross section and in 30 use are caused to slide over each other on their contiguous inclined sides 21. The blocks 17 are shown in Figs. 27 to 31 as consisting of four pieces *a'*, *a²*, *a³* and *a⁴* having beveled joining surfaces 19 and 20, and 35 inclined sides 21. The blocks 18 are shown in Figs. 32 to 35 as consisting of four pieces *b'*, *b²*, *b³* and *b⁴*, and the blocks 18' are shown in Figs. 36 to 40 as consisting of four pieces 40 *c'*, *c²*, *c³*, and *c⁴*, both blocks having beveled joining surfaces 19 and 20 and inclined sides 21 as in the blocks 17. The blocks 18 and 18' differ only in the curvature of their working 45 surfaces. In addition to the blocks 17, 18 and 18' I employ in this form of core, blocks 22 and 23 at the ends of the core, as indicated in Figs. 19 and 20. The block 22 is shown in detail in Figs. 23 to 26 as 50 consisting of two pieces *d'* and *d²* having beveled joining surfaces 24. The block 23, shown in Figs. 41 and 42, consist of two pieces *e'* and *e²* having beveled joining surfaces 55 25.

The blocks 17, 18, 18', 22 and 23 are assembled in a box or trough about a clamp bar comprising two members 26 and 27 having inclined bearing surfaces by which the bar is capable of contraction and expansion by a longitudinal movement of one member 60 upon the other effected by means of an eccentric 28 pivoted upon an extension of the member 27 and adapted to bear against the head 26' of member 26. At its other end the clamp bar is provided with a key 29 and a bearing block 30. When

the core blocks are assembled, a central opening 31 is provided throughout the core. The clamp bar is held against lateral movement by the end blocks 22 and 23, the opening 31, provided by the other blocks 17, 70 18 and 18' being sufficiently large to permit the necessary lateral movement of these blocks during the pressing operation. The clamp bar may be provided with stops 32 to limit the relative movement of the members thereof, and any one of a number of openings 33, provided at intervals in the bar, may receive the key 29 should it be desired to vary the number of blocks employed in the core. 75

It will be seen that in all the forms of blocks above described the lower pieces are provided with upper inclined surfaces to engage a corresponding surface on the upper pieces. Such formation of the blocks aids 80 in the collapse of the core when, after the action of the dies, the core is to be removed from the header, the upper pieces of the blocks tending to slide off the lower pieces or tending to act as a wedge to force the 85 lower pieces outwardly, according to the lead of the inclines. Also the described blocks provide a core which coacts with the dies uniformly in the production of successive headers, inasmuch as the core fills 90 the header and conforms exactly to the surfaces of the dies.

What I claim and desire to secure by Letters Patent of the United States, is:—

1. A core for the purpose described comprising a series of blocks each in elevation a parallelogram and each consisting of a plurality of pieces whose external surfaces are shaped to form a serpentine boiler-header, said pieces of each block being beveled for contraction of the core to facilitate its removal. 100

2. A core for the purpose described comprising a series of blocks each consisting of a number of pieces, all of said pieces having beveled faces adapted to contact with complementary beveled faces of two of the remaining pieces in planes transversely of the axis of the core formed by said blocks and means for preventing longitudinal 110 movement of the blocks during the operation of die-members. 115

3. A core for the purpose described comprising a series of blocks each divided substantially into quarters along planes intersecting each other internally of the blocks, a tie-member, and each of said blocks having an elongated aperture at the line of intersection of the dividing planes. 120

4. In means of the character described, 125 the combination with a pair of relatively movable dies having complementary projections and depressions for shaping intervening work, of a sectional core coacting with said dies and comprising a plurality 130

of sections opposite each projection and each depression and engaging the work at a multiplicity of points within each of the projections and of the depressions to act upon the work uniformly during a shaping operation by the dies.

5. In means of the character described, the combination with a pair of dies, of a core coacting therewith to form corrugations in intervening work, said core consisting of a series of rectangular blocks having pairs of parallel sides and faces, and a pair of similar complementary curved work-engaging ends adapted to mate with the coöperating face of a die, and means for holding said blocks with their faces in contact while the die members are acting to shape the work.

6. In means of the character described, the combination with a pair of dies, of a core coöperating therewith to shape intervening material, said core comprising a series of blocks having a pair of parallel faces, a pair of parallel sides, and a pair of complementary curved ends, each block consisting of a plurality of pieces having surfaces arranged at an angle to its faces and coöperating with similar surfaces on contiguous sections to facilitate contraction of the core in two directions when it is to be removed from the work.

7. In means of the character described, the combination with a pair of relatively movable dies having complementary projections and depressions for shaping intervening work, of a core coacting with said dies and comprising a series of blocks of which

there are a plurality coöperating with the complementary projections and depressions and conforming thereto in contour, each block comprising a plurality of sections having complementary coacting beveled edge faces extending from one to the other face of the block.

8. In a core of the class described, in combination, a series of shaping blocks adapted to conform the work to a predetermined shape and each of which comprises a number of sections, an expanding mechanism arranged internally of the blocks and comprising a plurality of bars having coacting inclined surfaces, and a pair of stops carried by said bars at opposite ends of the core whereby the blocks of the core may be held against separation during manipulation thereof.

9. In means of the character described, a pair of dies forming transverse crimps in tubes at an acute angle to the length of the tube, in combination with a core coacting with said dies and comprising a plurality of blocks having a pair of parallel faces inclined to the longitudinal axis of the core and each of which consists of a plurality of pieces, and means for holding said blocks with their contiguous faces in contact and against separation from one another.

In testimony whereof I have hereunto signed my name in the presence of two subscribing witnesses.

LINUS L. KARNS.
